(57) **CLAIM**

The ornamental design for a rat prevention device, as shown and described.

DESCRIPTION

FIG. 1 is an isometric view of a rat prevention device embodying my design;

FIG. 2 is a top plan view of the rat prevention device;

FIG. 3 is a bottom plan view of the rat prevention device;

FIG. 4 is a side view of the rat prevention device;

FIG. 5 is a side view of the rat prevention device;

FIG. 6 is a side view of the rat prevention device; and,

FIG. 7 is an isometric view of the rat prevention device in a position of use.

The toilet depicted by broken lines in FIG. 7 have been shown for the purpose of illustrating environmental features that form no part of the claimed design.
